(57) **CLAIM**

The ornamental design for an embroidery unit for sewing machine, as shown and described.

DESCRIPTION

FIG. 1 is a front elevational view of an embroidery unit for sewing machine showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a first perspective view thereof; and,

FIG. 8 is a second perspective view thereof.

The broken lines showing portions of the article in the drawings form no part of the claimed design. The long dash, short dash broken lines indicate the boundaries of the claimed design and form no part of the claimed design.

1 Claim, 8 Drawing Sheets
